L. S. FISHER, OF BROADHEAD, WISCONSIN.

Letters Patent No. 63,877, dated April 16, 1867.

IMPROVEMENT IN MODE OF HANGING AND GUIDING THE HARNESS IN LOOMS.

The Schedule referred to in these Letters Patent and making part of the same.

TO ALL WHOM IT MAY CONCERN:

Be it known that I, L. S. FISHER, of Broadhead, county of Greene, in the State of Wisconsin, have invented a new and improved "Loom;" and I do hereby declare that the following is a full and exact description thereof, reference being had to the accompanying drawing, and to the letters of reference marked thereon.

The nature of my invention consists in a certain improvement on the Henderson loom, patented January 1, 1861, and pertains to the hanging and guiding of the harnesses.

To enable others skilled in the art to make and use my invention, I will proceed to describe it.

In the Henderson loom above referred to, as well as most others, the harnesses are attached in pairs to the opposite end of a single strand, which plays over a pulley located centrally over the harnesses. This arrangement is very objectionable, as it does not insure perfect or accurate "shedding"—opening of the warp to receive the filling. Indeed, with it it is almost impossible to make a perfect "shed," as the harnesses are attached to each other and raised only by this central strand, consequently the ends of the harnesses have no positive vertical movement, and of course without a certain positive movement of both ends of the harness, that is, being parallel as well as vertical, (the top and bottom pieces remaining horizontal.) Without this movement of both ends of the harness the loom fails, as there can be no shedding without it, and without this movement or with no shedding the shuttle cannot pass and no filling can be received. This difficulty of keeping both ends of the harness at the same elevation, or of imparting to them the same vertical movement, as has been before said, my loom seeks to remedy. By my device I remedy the defects of Henderson and others as to hanging and guiding the harnesses. It may be Henderson sought but failed to accomplish my very aim by his guy and strand. I have overcome the difficulty, or insured a parallel as well as vertical movement, and preserved the horizontal position of the top and bottom pieces by attaching or pairing the harness, as will be described. In the drawings—

Figure 1 represents a perspective drawing of my loom.

Figure 2, the harness guide.

A A represent the frame, B B the harnesses. In the centre of their top pieces A' there is an eye, a, and in the ends are screw-eyes, b. Two cords, c, are fastened to the centre of each harness frame. These pass up and over pulleys d d, properly secured in top of frame, then passing over other pulleys f f, at the ends, pass down, and are attached to the outer ends of another harness to hooks b. This arrangement of attaching both ends of each harness to the central portion of another, (by-cords of equal length,) running over pulleys and both ends of the latter to the central portion of the former, secures an equal, uniform movement of all parts of the harness. F represents the guides for the ends of the harness. They are not rigid, but suspended, and have a vertical and horizontal adjustability, serving equally as well as rigid ones to keep the harness separate, so preventing them from rubbing or getting tangled together. G G' are weights suspended from cords g g', the end of each one being attached respectively to the web and cloth-beams, keeping the same "taut" on the beams, which are operated by the movement of the "lay" or batten in beating up, and it is essential that the movement of these beams in paying out the yarn and in taking up the cloth should be regulated. The catch or dog on the yarn-beam is only to be used when there is no yarn on beam, or when you desire to change the weights.

Having thus described my invention, what I claim as new, and desire to secure by Letters Patent of the United States, is—

1. Hanging the harness in looms in the manner substantially as shown and described and for the purpose set forth.
2. The adjustable guides F, in combination with the harnesses B B, constructed and operated in the manner as shown and described and for the purpose set forth.

L. S. FISHER.
